DESIGN FOR A TOY

Francis W. Werring, Haddon Heights, N. J.

Application April 25, 1944, Serial No. 113,366

Term of patent 7 years

(CL. D34—15)

To all whom it may concern:

Be it known that I, Francis W. Werring, a citizen of the United States, residing at Haddon Heights, in the county of Camden and State of New Jersey, have invented a new, original, and ornamental Design for a Toy, of which the following is a specification, reference being had to the accompanying drawing, forming part thereof, in which the single figure is a perspective view of a toy showing my new design.

The appearance of the opposite or far side of the toy is substantially the same as the appearance of the side shown.

I claim:

The ornamental design for a toy, substantially as shown and described.

FRANCIS W. WERRING.
